The ornamental device for a base for an enteral feeding device, as shown and described.

DESCRIPTION

FIG. 1 is a top view showing our new design of a base for an enteral feeding device;

FIG. 2 is an end view of a base for an enteral feeding device; and

FIG. 3 is a perspective view of a base for an enteral feeding device.

FIG. 4 is a cross-sectional end view of the base for an enteral feeding device taken along lines 4-4 in FIG. 1; and,

FIG. 5 is a cross-sectional side view of the base for an enteral feeding device taken along lines 5-5 in FIG. 1.

The broken lines shown in FIGS. 1-5 are for purposes of illustrating portions of the base for an enteral feeding device and form no part of the claimed design.
